United States Patent Office

Des. 205,540
Patented August 16, 1966

205,540

TURNER OR THE LIKE

Richard S. Latham, Chicago, Ill., assignor to American Home Products Corporation, New York, N.Y., a corporation of Delaware

Filed Dec. 3, 1965, Ser. No. 56

Term of patent 14 years

(Cl. D44—29)

Fig. 1

Fig. 2

Fig. 3

FIG. 1 is a front elevational view of a turner or the like showing my new design.

FIG. 2 is a side elevational view thereof.

FIG. 3 is a transverse section taken along line 3—3 of FIG. 1.

The dominant feature of my design resides in the portion shown in full lines.

I claim:

The ornamental design for a turner or the like substantially as shown and described.
